United States Patent Office

Des. 211,192
Patented May 28, 1968

211,192

DOLL

Martha C. Sager, 4420 Q St. N.W.,
Washington, D.C. 20007

Filed May 1, 1967, Ser. No. 6,888

Term of patent 14 years

(Cl. D34—4)

I claim:

The ornamental design for a doll, substantially as shown.
